BRAIDING MACHINE

Tillman T. Bunch, Towson, Md., assignor to Western Electric Company, Incorporated, New York, N. Y., a corporation of New York

Application February 25, 1948, Serial No. 10,660

13 Claims. (Cl. 87—44)

1

This invention relates to braiding machines, and more particularly to braiding machines for applying sheaths to electrical conductors.

An object of the invention is to provide new and improved braiding machines.

A further object of the invention is to provide braiding machines having a minimum number of parts arranged to cooperate accurately and efficiently in braiding strands of material at a high speed and with a minimum amount of vibration and noise.

A braiding machine illustrating certain features of the invention may include a group of cops, means for rotating the cops around a predetermined center in a predetermined direction, a second group of cops, means for rotating the second group of cops around the braiding center in a direction opposite to that of the first group of cops, and means for directing strands from the first group of cops alternately over and under the strands of the second group of cops. Each of the second group of cops is supported by a combined escapement support and drive including a pair of split rings, means for rotating the split rings in opposite directions, mutilated bearings supported by the split rings and serving to engage only portions of the split rings, means for moving a strand into the split rings, whereby the strand is moved past the split rings, and means for supporting one of the second group of cops from the bearings.

A complete understanding of the invention may be obtained from the following detailed description of a braiding machine illustrating certain features thereof, when read in conjunction with the appended drawings, in which:

Fig. 1 is a fragmentary, top plan view of a braiding machine illustrating one embodiment of the invention;

Fig. 2 is an enlarged, vertical section taken along line 2—2 of Fig. 1;

Fig. 3 is an enlarged, horizontal section taken along line 3—3 of Fig. 2;

Fig. 4 is an enlarged, vertical section taken along line 4—4 of Fig. 3;

Fig. 5 is an enlarged, horizontal section similar to Fig. 3;

Fig. 6 is an enlarged, vertical section taken along line 6—6 of Fig. 5;

Fig. 7 is an enlarged, horizontal section similar to Fig. 3;

Fig. 8 is an enlarged, horizontal section taken along line 8—8 of Fig. 7;

Fig. 9 is an enlarged, horizontal section similar to Fig. 3;

2

Fig. 10 is an enlarged, horizontal section taken along line 10—10 of Fig. 9, and

Fig. 11 is an enlarged, vertical section similar to Fig. 2 of a braiding machine illustrating an alternative embodiment of the invention.

Referring now in detail to the drawings, there is shown therein a plurality of cop carriers 20, 21 and 22 of a ring of cop carriers being rotated in a counterclockwise direction, as viewed in Fig. 1, around an elongated core 25 to carry strands 26—26 from cops 28—28 around the core 25 in that direction. Cop holders 30, 31 and 32 of a second and lower ring of cop carriers are revolved around the core 25 in a clockwise direction, and strands 36—36 from cops 38—38 carried by the cop holders of this group are interwoven with the strands 26—26 to form a braided covering 39 (Fig. 2) upon the core 25. The cop holders 30, 31 and 32 are rigidly connected to a spindle 40, which carries a ring gear 42 therewith.

A spindle 44 revolved around the core 25 in a counterclockwise direction, as viewed in Fig. 1, is provided with an apron 46 (Fig. 2) integral therewith. The cop carriers of the group including the carriers 20, 21 and 22 are each supported on the apron 46 by identical escapement supports and drives. Since the escapement drives are identical, only an escapement support and drive 47 of the cop carrier 21 will be described in detail.

Stub shafts 48 and 50 are mounted rotatably in radial and thrust bearings 52 and 54, respectively, carried by the apron 46. Intermeshing gears 56 and 58 are fastened rigidly to the shafts 48 and 50, respectively, and the gear 58 meshes with an idler gear 59 which meshes with the ring gear 42 so that the shafts 48 and 50 are rotated in opposite directions as they and the idler gear are carried around the core 25 in one direction and the ring gear 42 is revolved therearound in a direction opposite thereto. Helical cam posts 60 and 62 project from the shafts 48 and 50, respectively, from portions thereof near the peripheries thereof and support split rings 64 and 66, respectively, which are provided with gaps 68 and 70 (Fig. 3).

The strands 36—36 pass through guides 74—74 (Fig. 1) from the cops 38—38 and pass from the guides 74—74 to the core 25, and over stationary deflectors, illustrated by a deflector 78, which deflect the strands 36—36 upwardly over alternate ones of the cop holders 20, 21 and 22. Stationary deflectors, illustrated by a deflector 78, deflect the strands 36—36 alternately downwardly under the cop holders 30, 31 and 32 so that the strands 36—36 are interbraided with the strands 26—26.

Holders 79—79 hold the strands in their deflected positions between deflections. As one of the strands 36—36 is moved under the cop carrier 21, cam guides 80 and 82 guide that strand laterally between the rings 64 and 66 and the tops of the shafts 48 and 50, respectively, to a position illustrated in Figs. 3 and 4, in which position the strand 36 bears against the cam posts 60 and 62. As the cam posts revolve continuously in opposite directions, they push the strand 36 through the gaps 68 and 70, respectively, to a position in which the portions of the strand 36 approaching the split ring 64 and leaving the split ring 66 are on top of the split rings so that the strand passes into the split rings 64 and 66.

The rings 64 and 66 are mounted rotatably in arcuate bearings 90 and 92 formed in a shoe 94 and a support 96 so that the strand 36 is free to pass through the split ring 66 from the bottom thereof, as viewed in Fig. 4, and passes continuously through the rings as the rings are rotated. The rotation of the rings moves the gaps 68 and 70 therein through the arcuate bearings 90 and 92, respectively, and when the openings reach the ends of the arcuate bearings 90 and 92, the portions of the strand 36 which had been positioned below the rings snap upwardly through the openings 68 and 70 in the rings, whereby the strand 36 is disengaged from the rings 64 and 66 and is on the opposite side of the cop carrier 21 from that at which the strand approaches this cop carrier.

The cam 80 aids the helical post 60 in deflecting the strand 36 upwardly through the opening 68, and with the cam 82, serves to guide the strand 36 between the rings 64 and 66 and the tops of the shafts 48 and 50. The cam 82 holds the portion of the strand 36 engaged by it down as the strand 36 is moved into the surfaces between the upper ends of the shafts 48 and 50 and the rings 64 and 66, respectively, but permits the right hand portion of the strand 36, as viewed in Fig. 4, to be moved upwardly by the cam post 62 and a cam 98 carried on the apron 46. Thus, both the cam 80 and the cam post 60 tend to move the strand 36 initially to a position passing through the split ring 64, and the cam 98 and the cam post 62 tend to move the strand 36 initially through the opening 70 in the split ring 66.

As the openings 68 and 70 in the rings 64 and 66 again come into registry with the strand after the openings pass through the bearings 90 and 92, the tension in the strand itself snaps the strand quickly through the openings 68 and 70. Since the portion of the strand just entering the ring 64 and the portion of that strand just leaving the ring 66 are above the rings 64 and 66 and the portion of the strand 36 between these portions is below the rings 64 and 66, the latter portion is moved up by the tension on the strand as the rings move out of contact with that portion of the strand that the rings were holding down.

Operation

The carrier 21 is carried and rotated in a counterclockwise direction, as viewed in Fig. 1, around the core 25 by the apron 46, the shafts 48 and 50, the support 96 and the elements associated therewith. All the other carriers in the group including the carrier 21 are similarly carried and rotated by elements corresponding to the shafts 48 and 50, the support 96 and the elements associated therewith. The strands 36—36

5 are deflected upwardly over and downwardly under the cop carriers 20, 21 and 22, by deflectors, illustrated by the deflectors 76 and 78, respectively, and whenever any of the strands 36—36 is passed under the cop carrier 21, that strand is guided between the upper ends of the shafts 48 and 50 and the split rings 64 and 66, respectively.

The strand 36 is deflected upwardly through the opening 68 in the ring 64 by the cam 80 and the cam post 60, and simultaneously is deflected upwardly through the opening 70 in the ring 66 by the cam 98 and the cam post 62 so that the strand passes through the openings 68 and 70 simultaneously. The strand then passes through the rings 64 and 66 to the core 25 (Fig. 2) while the rings 64 and 66 are rotated in the arcuate bearings 90 and 92, respectively, until the openings 68 and 70 reach the ends of bearings 80 and 82 at which time the tension on the strand 36 and the action of the cam posts 60 and 62 move the portion of the strand 36 positioned at a level below the rings 64 and 66 upwardly through the openings 68 and 70 to free the strand from the rings 64 and 66.

20 The openings 68 and 70 are rotated in opposite directions and are indexed with respect to each other in a relationship in which the openings always face in opposite directions as the openings cross a line extending through the centers of the rings 64 and 66, and the angle subtended by each of the bearings 90 and 92 is sufficient that the bearings 90 and 92 always engage a substantial portion of the solid portions of the rings 64 and 66 on both sides of the line through the centers of the rings. Hence, the support 96 and the shoe 94 are always held by the rings 64 and 66 against thrust in any direction and there is no noise or vibration from the rotation of the rings 64 and 66 in the bearings 90 and 92, respectively.

25 Whenever one of the strands 36—36 is deflected under one of the cop carriers 20 and 22, the strand is passed from one side of that cop carrier by escapement means identical with the escapement means described hereinabove for supporting the cop carrier 21 and for clearing the strand therewith.

Alternative embodiment

30 A braiding machine forming an alternative embodiment of the invention is shown in Fig. 11, and is identical with the machine shown in Figs. 1 to 10, inclusive, except for escapement supports and drives, of which an escapement support and drive 147 is shown. The drive 147 is identical with the drive 47 except that the drive 147 includes rigid helical guides 148 and 150 rather than the shafts 48 and 50 of the drive 47.

35 The operation of the drive 147 is identical with that of the drive 47 except that the helical guides 148 and 150 turn split rings 164 and 166, respectively, rapidly in opposite inrunning directions. The helical guides 148 and 150 are formed in such directions that they move a strand 136 rapidly upwardly toward the split rings when the strand is engaged by any portions of the helices. The helical guides 148 and 150 are sufficiently long that they catch the strands even if they have been deflected out of their usual paths.

40 The above-described escapement drives, illustrated by the escapement drives 47 and 147, are the sole supports and drives of the group of cop carriers including the carriers 20, 21 and 22 and the carriers corresponding thereto. Consequent-

ly, vibrations, shocks and noise inherent in the operation of other types of braiding machines, such as those supporting cop carriers on slotted guide tracks, or the like, are eliminated. Furthermore, the drives 47 and 147 are much less complicated in construction and operation than carrier supports and drives known hitherto.

What is claimed is:

1. In a braiding machine including a group of cops, means for revolving the cops around a predetermined center in a predetermined direction, a second group of cops, means for revolving the second group of cops around said center in a direction opposite to that of the first group of cops and means for directing strands from the first group of cops alternately over and under the strands of the second group of cops, a plurality of escapement supporting and driving devices for the first group of cops, each of which comprises a pair of split rings, means connected to the rings at points on the rings off-center with respect to the rings for rotating the split rings, mutilated bearings supported by the split rings and serving to engage only portions of the split rings, means for moving a strand laterally into the split rings, said rings and said bearings serving to permit the strand to be moved laterally out of the split rings as the rings are rotated, and means supported by the bearings for supporting one of the first-mentioned cops.

2. An escapement support and drive, which comprises a pair of split rings, revolvable posts connected to the rings for rotating the split rings, means for revolving the split rings around a braiding center in a predetermined direction, a support having a pair of mutilated bearings supported by the split rings for engaging only portions of the split rings, means for guiding laterally into the split rings a strand being moved laterally in a direction opposite to the direction of revolution of the rings, and means for tensioning the strand, whereby the strand is pulled laterally out of the split rings.

3. An escapement support and drive for a cop carrier, which comprises a support having a pair of arcuate bearings formed therein, a pair of split rings having openings between the ends thereof mounted for rotation in the bearings, means for supporting the rings from one end of each and for rotating the rings in the bearings, and means for guiding a strand laterally through the openings in the rings, whereby the rings and the ring-supporting means carry the strand laterally from one side of the support to the other thereof.

4. An escapement support and drive for a cop carrier, which comprises a support provided with a pair of arcuate radial-and-thrust bearings, a pair of split rings mounted rotatably in the bearings, the arcuate length of each of the bearings less the arcuate length of the opening in the split ring mounted rotatably in that bearing being greater than 180°, revolvable posts connected to the rings for rotating the rings in the bearings and for supporting the split rings, whereby the support is supported by the rings, means for moving a strand laterally through the openings in the rings, and means for moving the strand laterally out of the rings as the rings are rotated.

5. An escapement support and drive for a cop carrier, which comprises a support provided with a pair of discontinuous radial-and-thrust bearings positioned with the axes thereof substantially parallel for supporting a cop, the openings between the ends of each of the bearings being on the same side of the support, a pair of discontinuous

tinuous rings mounted rotatably and interlockably in the bearings, the angle subtended by each of the bearings less that subtended by one of the openings between the ends of the rings interlocked therewith being greater than 180°, a pair of posts connected rigidly to the rings one at one end of each of the rings, said posts and the ends of the rings to which they are connected serving to form cams, means for revolving the posts around the axes of the rings to rotate the rings in the bearings, said post-revolving means serving to index the posts to keep the openings between the ends of the annuli 180° out of phase and to rotate the posts and annuli in such directions that the cams formed thereby tend to push a strand laterally through the openings in the rings, and means for tensioning the strand.

6. An escapement support and drive for a cop carrier, which comprises a support provided with a pair of discontinuous radial-and-thrust bearings positioned in substantially the same plane for supporting a cop, the openings between the ends of each of the bearings being on the same side of the support, a pair of discontinuous annuli mounted rotatably and interlockably in the bearings, the angle subtended by each of the bearings less that subtended by one of the openings between the ends of one of the annuli being greater than 180°, a pair of posts connected rigidly to the annuli one at one end of each annulus, said posts and the ends of the annuli to which they are connected serving to form helices, means for revolving the posts around the axes of the annuli in inrunning directions to rotate the annuli in the bearings in inrunning directions, said post-revolving means serving to index the posts to keep the openings between the ends of the annuli 180° out of phase and to rotate the posts and annuli in such directions that the helices formed thereby tend to push a strand laterally through the openings in the annuli, means for revolving the post-revolving means around a predetermined center, strand-guiding means for pushing such a strand laterally through the openings between the ends of the annuli, and means for tensioning the strand.

7. An escapement support and drive for a cop carrier, which comprises a support having a pair of arcuate bearings formed therein, a pair of split rings having openings between the ends thereof mounted for rotation in the bearings, and a pair of helical guides one secured rigidly to one end of each of the rings for supporting the rings, means for rotating the helical guides to rotate the rings in the bearings and for guiding a strand laterally through the openings in the rings, whereby the rings and the helical guides carry the strands laterally from one side of the support to the other thereof.

8. An escapement support and drive for a cop carrier, which comprises a support having an arcuate bearing formed therein, a disc having a slot therein mounted for rotation in the bearing, a helical guide secured rigidly to the disc for supporting the disc, and means for rotating the helical guide so that it guides a strand laterally into the slot in the disc.

9. An escapement support and drive for a cop carrier, which comprises a support provided with a pair of arcuate radial-and-thrust bearings, a pair of split rings mounted rotatably in the bearings, the arcuate length of each of the bearings less the arcuate length of the opening in the split ring mounted rotatably in that bearing being greater than 180°, a pair of helical guides for

supporting the split rings and means for rotating the guides to rotate the rings in the bearings, whereby a strand moved laterally into the helical guides is moved laterally through the openings between the ends of the rings.

10. An escapement support and drive for a cop carrier, which comprises a support provided with a pair of discontinuous radial-and-thrust bearings positioned with the axes thereof substantially parallel for supporting a cop, the openings between the ends of each of the bearings being on the same side of the support, a pair of discontinuous rings mounted rotatably and interlockably in the bearings, the angle subtended by each of the bearings less than subtended by one of the openings between the ends of one of the rings being greater than 180°, a pair of helical guides connected rigidly to the rings one at one end of each, means for rotating the guides around the axes of the rings to rotate the rings in the bearings, said revolving means serving to index the guides to keep the openings between the ends of the rings 180° out of phase and to rotate the guides in such directions that the guides tend to push a strand laterally through the openings in the rings, and means for tensioning the strand.

11. A cop carrying device, which comprises a spindle rotatable about a predetermined axis, means for rotating the spindle about said axis in a predetermined direction, a pair of posts spacedly mounted on the spindle for revolution about axes generally parallel to the axis of the spindle, a pair of split rings one connected generally perpendicularly to an end of each of the posts, means for revolving the posts, a cop carrier, and a pair of mutilated radial and thrust bearings mounted on the split rings and carrying the cop carrier, each of said bearings being cut away on the side thereof in advance as the spindle is rotated so that a strand may be guided into the rings.

12. A cop carrying device, which comprises a spindle rotatable about a predetermined axis,

means for rotating the spindle about said axis in a predetermined direction, a pair of posts mounted on the spindle for revolution about axes generally parallel to and spaced apart along a line generally radial to the axis of the spindle, a pair of split rings one connected perpendicularly to an end of each of the posts, means for revolving the posts, a cop carrier, a pair of mutilated radial and thrust bearings mounted on the split rings and carrying the cop carrier in a position in which its longitudinal axis is substantially radial with respect to the spindle, each of said bearings being cut away on the side thereof in advance as the spindle is rotated, and means for guiding a strand laterally into the rings.

13. A cop carrying device, which comprises a spindle rotatable about a predetermined axis, means for rotating the spindle about said axes in a predetermined direction, a pair of cam posts mounted on the spindle for revolution about axes generally parallel to and spaced apart along a line generally radial to the axis of the spindle, a pair of split rings one connected perpendicularly to an end of each of the cam posts, means for revolving the posts, a cop carrier, and a pair of mutilated radial and thrust bearings mounted on the split rings and carrying the cop carrier in a position in which its longitudinal axis is substantially radial with respect to the spindle, each of said bearings being cut away on the side thereof in advance as the spindle is rotated so that a strand may be guided laterally into the rings by the cam posts.
